US0D1096914S

(12) **United States Design Patent** (10) **Patent No.:** **US D1,096,914 S**
Muhlenkamp, IV et al. (45) **Date of Patent:** **** Oct. 7, 2025**

(54) **CAMERA MOUNT**(71) Applicant: **GoPro, Inc.**, San Mateo, CA (US)(72) Inventors: **John George Muhlenkamp, IV**,
Mapleton, UT (US); **Akshay Shinde**,
Sunnyvale, CA (US); **Huy Phuong
Nguyen**, Alpine, UT (US); **Nicholas D.
Woodman**, Big Sky, MT (US)(73) Assignee: **GoPro, Inc.**, San Mateo, CA (US)(***) Term: **15 Years**(21) Appl. No.: **29/949,801**(22) Filed: **Jun. 28, 2024**

FIG. 1 is a front, upper, right perspective view of a camera mount of our new design;

FIG. 2 is a rear, lower, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.
